UNITED STATES PATENT OFFICE.

ARTHUR SHORROCK, OF NORTH ADAMS, MASSACHUSETTS.

MIXING-SLAB.

1,218,327.

Specification of Letters Patent.

Patented Mar. 6, 1917.

Application filed January 5, 1916. Serial No. 70,427.

To all whom it may concern:

Be it known that I, ARTHUR SHORROCK, a citizen of the United States, and a resident of North Adams, in the county of Berkshire and State of Massachusetts, have invented 5 certain new and useful Improvements in Mixing-Slabs, of which the following is a specification.

My invention relates to dental mixing 10 slabs whereon it is desired to mix certain materials at a predetermined temperature, and the main object thereof is to provide self-contained means in such slabs for determining the temperature thereof.

15 The manufacturers of certain compounds, particularly dental cements, demand that their products be mixed for use at a certain temperature in order to attain the best results, and this requires that the mixing slab 20 used by dentists for mixing the powder into paste form just previous to use shall be at the desired temperature, but no means for determining whether or not the slab is at the desired temperature are now obtainable, 25 and it was in order to fill this want that my invention was conceived.

My invention is fully described in the 30 following specification, of which the accompanying drawings form a part, in which like characters refer to like parts in each of the views, and in which:—

Figure 1 is a top plan view of a mixing slab constructed in accordance with my invention; and Fig. 2 is a section taken on 35 the line 2—2 of Fig. 1.

My invention comprises a slab 3 of transparent material, such as glass or the like, of a suitable thickness insuring immunity from easy breakage, provided with a groove 4 in 40 the under side thereof to receive a mercury tube 5 in such a manner as to be readable from the upper side of the slab and be protected against accident at the under side thereof.

The tube may be cemented in the groove 4 45 of held therein in any desired manner, and a scale may be engraved or otherwise applied in or on the upper surface of said slab to form a thermometer with the tube 5.

I may also provide a recess in the under 50 side of the slab to receive a combined thermometer and scale, this not being illustrated however, or I may combine the slab and thermometer in any other desired manner 55 provided that it may be read at the upper surface of said slab.

In practice the slab is chilled or heated to the desired temperature as indicated by the thermometer, as by immersion in cold or hot water, after which the slab is ready for 60 mixing, the material of which the slab is formed holding this temperature for a sufficiently long time to attain the best results with the material being mixed, but I do not limit myself to any specific material, nor to 65 any particular form.

Having fully described my invention, what I claim as new and desire to secure by Letters Patent, is:—

A dental mixing slab provided with a 70 groove in the under side thereof of relatively small length and width and of relatively great depth whereby said slab will not be materially weakened by said groove, a mercury tube in said groove adjacent the upper 75 surface of said slab, and means for sealing said tube in said groove, said slab being provided with a scale adjacent said tube to form a thermometer therewith.

In testimony whereof I have signed my 80 name to this specification in the presence of two subscribing witnesses.

ARTHUR SHORROCK.
